UNITED STATES PATENT OFFICE.

SAM F. KLOHS, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

CARLINE STRUCTURE.

1,109,340.

Specification of Letters Patent.

Patented Sept. 1, 1914.

Application filed March 28, 1912. Serial No. 686,817.

To all whom it may concern:

Be it known that I, SAM F. KLOHS, a citizen of the United States, residing in Chicago, in the county of Cook and State 5 of Illinois, have invented a new and useful Improvement in Carline Structures, of which the following is a specification.

This invention relates to improvements in carline structures of car roofs.

10 The object of the invention is to provide a carline structure which is light, yet relatively strong and rigid, cheap to manufacture, easily assembled, and which provides a strong junction between the carline and 15 the side plates of the car particularly adapted to resist the strains which occur in the roof structure.

My invention furthermore consists in the improvements in the parts and devices and 20 in the novel combinations of the parts and devices as herein shown, described, or claimed.

In the drawing forming a part of this specification, Figure 1 is a partial, trans- 25 verse, sectional view of a car roof showing my improvements applied thereto. Fig. 2 is a detail, plan view showing the structure used at the junction of one end of the carline to the side plates. Fig. 3 is a sectional view upon an enlarged scale taken on the line 3—3 of Fig. 1, and Fig. 4 is a perspective view of the bracket or supporting member used in my improved construction.

In the drawing 10, 10 denote the side, 35 plates of the car roof which may be of any suitable material; 11, 11 the side boards of the car having secured thereto at the upper end the fascia boards 12, 12. Each side plate 10 has secured thereto an angle bar 40 13 by means of bolts 14, the bars 13 extending along the sides of the cars.

Secured to each of the angles 13 at each point where a carline is to be used are malleable, cast brackets or supporting members 45 15, each comprising a flat plate portion 16, a pair of upwardly parallelly arranged flanges or ribs 17, the same being adapted to form a channel in conjunction with the flat portion 16, and a depending flange or 50 rib 18 on the under side of the plate 16, the rib 18 being disposed at a distance from the outer edge of the plate 16. The flanges or ribs 17 are located intermediate the ends

of the plate portion 16 and the latter is preferably tapered on its ends as shown at 19 55 so that the plate 16 forms a support or brace for each of the flanges 17 to prevent the same from spreading apart.

Each carline, which in the form shown in the drawing, comprises a commercially 60 rolled channel 20 is adapted to have each end fit in the channel formed by the members 17 and 16 and to be secured to the bracket 15 by means of bolts or other suitable fastening devices 21, each end of the 65 carline being preferably extended over the side plate 10 and secured thereto by a bolt 22. Each carline or channel 20 is provided with a filler or nailing block 23 to which the purlins 24 and the ridge pole 25 are secured 70 for supporting the outside roof boards 26.

In the structure which I have shown, it will be seen that the angle iron 13 forms a rigid structure for securing the bracket 15 75 to the side plate, since the inner edge of the substantially horizontally extending leg of the angle iron abuts the depending flange 18 of the bracket and thus prevents the bracket from twisting relatively to the side 80 plate. Furthermore, the flanges 17 between which the carline is seated prevent the latter from twisting relatively to the bracket and hence from twisting relatively to the side plate.

85 I claim:

1. In a carline structure, in combination: the side plates of a car; a carline extending from one side plate to the other and resting on the tops of the same; and metal brackets 90 attached to the under side of the carline and at a distance from the ends of the same, such brackets having vertical side flanges closely embracing the carline so as to provide lateral extensions beyond the side flanges, 95 vide a carline-receiving space open at its top and a horizontal bottom plate formed with which bottom plate and extension have wide bearings against the inner sides of the car frame; substantially as specified.

2. In a carline structure, in combination; the side plates of a car; a carline extending from one side plate to the other and over the tops of and resting on the same; longitudinal metal bars secured to the inner sides 100 of the side plates; and metal brackets at

tached to the under side of the carline and at a distance from the ends of the same, such brackets having vertical flanges closely embracing the sides of the carline and a 5 horizontal bottom plate formed with lateral extensions beyond the side flanges, the said brackets having depending flanges abutting

against the inner sides of the said longitudinal metal bars and having a wide bearing on the same; substantially as specified.

SAM F. KLOHS.

ESTHER ABRAMS.

Copies of this patent may be obtained for five cents each, by addressing the "Commissioner of Patents, Washington, D. C."

It is hereby certified that in Letters Patent No. 1,109,340, granted September 1, 1914, upon the application of Sam F. Klohs, of Chicago, Illinois, for an improvement in "Carline Structures," an error appears in the printed specification requiring correction as follows: Page 1, line 95, as now numbered, should follow present line 97; and that the said Letters Patent should be read with this correction therein that the same may conform to the record of the case in the Patent Office.

Signed and sealed this 20th day of October, A. D., 1914.

[SEAL.]

J. T. NEWTON,

Acting Commissioner of Patents.
